UNITED STATES PATENT OFFICE

MAURICE B. COOKE, OF PLAINFIELD, NEW JERSEY, ASSIGNOR TO THE ATLANTIC REFINING COMPANY, OF PHILADELPHIA, PENNSYLVANIA, A CORPORATION OF PENNSYLVANIA

METHOD OF FRACTIONATION

Original application filed July 24, 1925, Serial No. 45,796. Divided and this application filed March 21, 1929. Serial No. 348,734.

This invention relates to improvements in the art of fractionation, and refers more particularly to a method of treating vapors, such as those of oil, acid, or any type of material, to produce close fractionation or to obtain fractions having a restricted range of boiling points.

My invention resides in a method of the character hereinafter described and claimed.

10 This application is a division of my prior application, Serial No. 45,796, filed July 24, 1925.

As specific examples of some of the forms an apparatus for carrying out my process 15 may take, reference is had to the accompanying drawing, in which:

Fig. 1 is a sectional side view of a preferred type of tower.

Fig. 2 is a sectional plan view taken on line 2—2 of Fig. 1, with parts broken away to show various parts.

Fig. 3 is a vertical sectional view, partly in elevation, of a modified construction.

Referring to the drawings, at 1 is shown the usual type of fractionating tower which is preferably cylindrical in form. Vapors are introduced into the tower through a vapor inlet 2 at the bottom of the tower and discharged at an upper vapor outlet 3. Within the tower are positioned a plurality of trays 4 equipped with risers 4^a which conduct upwardly the vapors introduced at the bottom of the tower. Surmounting these risers are caps 5 which direct the vapors through the several pools of liquid upon the trays 4. These caps have preferably a serrated lower edge as shown at 6, which serves to break up and more evenly distribute the vapors whose flow is reversed upon discharge from the risers by means of the cup-shaped domes of the caps. The vapors passing through the toothed or serrated edges of the caps, percolate through the several pools of liquid supported upon the trays, the depth of each pool being determined by the height of the upper ends of the downcomer or overflow standpipes 7 above the bottoms of the respective trays. With the accumulation of condensate in the pools, the excess material overflows 50 through the tops of the standpipes 7 to the

next succeeding pools below. Thus the reflux material is gravitated downwardly against the passage of the rising vapors.

The tops of the caps are shaped to form a flat surface or grid designated as 8 in the drawings. The tops of the caps shown are hexagonal in form in order that they fit together to form a continuous flat surface or grid upon which is placed the packing material diagrammatically shown at 9. The tops 8 are perforated by holes 10 which serve to permit a free passage of the vapors which rise about the serrated edges of the caps and pass upwardly through the flat top grid and packing material 9 carried thereupon.

In place of the caps described and shown in Fig. 1, the usual type of bubbler cap 5^a may be used as shown in Fig. 3. These bubbler caps serve the purpose of reversing the flow of the vapors and causing the same to percolate through the pools of liquid supported upon the separate trays in the tower. Between the trays is positioned an annular member 11 carried by the angle supports 12. To this member 11 is bolted a circular perforated grid 12' disposed at the opening of member 11. This grid supports the packing material 9 in a manner similar to the supporting grid formed by the fitted tops 8 of the caps 5 shown in the first two figures of the drawing. It is understood that, if so desired, a grid such as that shown at 12' will be interposed below each of the bubble tower pools throughout the length of the tower such as that partially shown in Fig. 3. Otherwise, the construction of the tower is identical in form to the usual type of bubble tower construction having the pools emptying into the pools below through the overflow standpipes 7, while the vapors rise through the successive trays by means of risers 4^a surrounded by bubble caps 5^a.

From the separate pools, if so desired, liquid condensates or fractions may be drawn off through the lines 13, the heaviest material passing off from the fluid delivery line 14. In actual operation, a bubble tower fractionator is recognized as one of the most efficient types of mechanism, as a relatively close fractionation is attained and a most complete

and intimate contact of the condensate and vapors makes for a uniform final product as well as fractions of restricted boiling point range. It is, however, appreciated that there is a certain amount of mist or liquid carried along or entrained in the vapors as they percolate through the liquid pools. The bursting of the bubbles, caused by the vapors during their percolation through the pools, releases a considerable quantity of liquid mist which is readily taken up and carried along with the vapors. This entrained material is difficult of separation due to its light weight and a supporting movement or energy set up by the velocity of the vapors which readily carries this material along through the successive pools and overhead to the final condensing zone where it adds undesirable constituents to the final product. By interposing between the pools a vapor arrester of this character or a similar type which has the de-entraining effect upon the vapors, and particularly effects removal of entrained liquid from the vapors to cause the same to be separated out and trapped back to the pool below, a much closer fractionation is effected and a more desirable final product produced as well as the intermediate fractions which may be drawn off from the individual pools.

30 A feature of particular importance is that the reflux liquid in passing downwardly through the column is not permitted to come into contact with the vapors from which the entrained liquid has been removed. This is 35 of particular importance in that if the reflux liquid were permitted to come into contact with the disentrained vapors, re-entrainment would take place and permit the vapors to pass to the next plate above carrying with them substantial quantities of entrained liquid.

It shall be understood that my invention is not limited to specific details as herein set forth, and that my invention comprehends 45 the utilization of equivalent methods.

What I claim is:

1. In the art of fractionation, the process which comprises passing vapors through a fractionating column countercurrent to reflux liquid which forms a series of pools, causing 50 said vapors in their passage to contact successively with the pools of liquid, prior to the passage of the vapors into contact with a pool of the liquid causing them to impinge 55 upon surfaces thereby to remove from the vapors substantially all of the liquid entrained therein, and conducting the vapors, in substantially liquid-free condition and without again bringing them into contact with the 60 liquid so removed, through a vapor zone in the column to a succeeding pool of liquid.
2. In the art of fractionation, the process which comprises passing vapors through a fractionating column countercurrent to reflux liquid which forms a series of pools,

causing said vapors in their passage to contact successively with the pools of liquid, after contacting the vapors with a pool of the liquid causing them to impinge upon surfaces thereby to remove from the vapors substantially all of the liquid entrained therein, 70 delivering the liquid so removed to a pool of liquid which the vapors have theretofore passed, and conducting the vapors, in substantially liquid-free condition and without again bringing them into contact with the liquid so removed, through a vapor zone in the fractionating column.

3. In the art of fractionation, the process which comprises passing vapors upwardly 80 through a fractionating column, passing reflux liquid downwardly through said column, permitting the liquid in its passage downwardly to form a series of pools, causing said vapors in their passage upwardly to contact successively with the pools of liquid, causing 85 the vapors after their passage through one of said pools of liquid to impinge upon surfaces thereby to remove from the vapors substantially all of the liquid entrained therein, returning the liquid so removed to the pool of liquid last mentioned, conducting the vapors, in substantially liquid-free condition and without again bringing them into contact 90 with the liquid so removed, through a vapor zone in the column to the pool of liquid next above, and conducting liquid from the last mentioned pool to the pool below without permitting such liquid to come into contact 95 with the rising substantially liquid-free 100 vapors.
